UNITED STATES PATENT OFFICE

109,264

DESIGN FOR A FUR SCARF

Irving Cohen, New York, N. Y.

Application January 22, 1938, Serial No. 74,480

Term of patent 3½ years

To all whom it may concern:

Be it known that I, Irving Cohen, a citizen of the United States and residing in Manhattan, in the city, county, and State of New York, have invented a new, original, and ornamental Design for a Fur Scarf, of which the following is a specification, reference being had to the accompanying drawings, forming part thereof.

Fig. 1 is a rear view of the scarf worn bolero fashion.

Fig. 2 is a front view of Fig. 1.

The stippled portions on the drawings represent a fabric lining.

I claim:

The ornamental design for a fur scarf substantially as shown and described.

IRVING COHEN.
